(57) **CLAIM**

The ornamental design for a motorcycle triangle headlight,
as shown and described.

DESCRIPTION

FIG. 1 is a bottom, front, right side perspective view of a
motorcycle triangle headlight showing my new design;
FIG. 2 is a top, rear, right side perspective view thereof;
FIG. 3 is a top, front, right side perspective view thereof;
FIG. 4 is a bottom plan view thereof;
FIG. 5 is a top plan view thereof;
FIG. 6 is a left side elevational view thereof;
FIG. 7 is a right side elevational view thereof;
FIG. 8 is a front elevational view thereof; and,
FIG. 9 is a rear elevational view thereof.

The broken lines show the features of the motorcycle
triangle headlight that form no part of the claimed design.
